FOLDING COAT HANGER

Lola F. McKnelly and Charles J. McKnelly,
Spokane, Wash.

Application June 24, 1946, Serial No. 678,998

1 Claim. (Cl. 223—94)

1

This invention relates to a garment hanger and it is one object of the invention to provide a garment hanger so constructed that it may be folded into a small and compact packet, which may be carried in a purse, or a person's pocket or handbag.

Another object of the invention is to provide a garment hanger, formed of sections, which may be easily folded upon each other to form an article of lesser size when not in use.

Another object of the invention is to provide a plastic garment hanger, having hinged sections which fold one upon another, thus, shortening the length of the hanger, providing a compact packet which may be carried in a purse, and be unfolded for use when other hangers are not available.

Another object of the invention is to provide a garment hanger which is simple in construction, durable, and inexpensive to manufacture.

The invention is illustrated in the accompanying drawing wherein:

Fig. 1 is a side view in elevation of the improved garment holder.

Fig. 2 is a plan view shown in semi-folded position.

Fig. 3 is a sectional view taken on line 3—3 of Fig. 1.

Fig. 4 is a view in side elevation of a modified form.

Fig. 5 is a plan view of Fig. 4 showing the dotted position of folding the garment hanger.

This improved garment hanger includes in its construction, a coat hanger 1 formed from plastic and having its intermediate sections 2 and 3 formed with laterally projecting hinge ears 4. The hinge pin 5, which forms a pintle for the hinge, passes vertically through the ears 4 and terminates in an eyelet 6, at its upper end. A hook 7 having an eye at its lower end is pivotally attached to the eyelet 6 by inserting a rivet 9 through the eyelets of the hook and the pin and securing it in place. When folding the hanger, the hook 7 is folded to the dotted position as shown in Fig. 1, and the intermediate sections are folded toward each other as shown in Fig. 2. The end portions 10 and 11, which are hinged at 12 and 13 are folded forward and lie parallel to sections 2 and 3, when completely folded into a packet. The hinges for the meeting ends of the sections 2, 3, 10, and 11 project laterally from sides of the sections so that the sections are aligned when extended and permitted to have flat face to face engagement with each other when folded. It should also be noted that the com-

panion ears of the hinges fit close against each other and have frictional binding engagement with each other so that the sections will be held in an extended position or a folded position. In addition meeting ends of the sections have abutting and close fitting engagement with each other when extended. Therefore tight joints are formed between the sections.

A horizontal lip 14 is provided on the upper edge 10 of the sections extending lengthwise thereof and provides a shelf for the garment which prevents creasing.

In Figures 4 and 5 there has been shown a garment hanger of modified construction wherein the hanger is divided into three sections. The intermediate section 15 is provided with end sections 16 and 17 hinged at 18 and 19 in such a manner that they fold against opposite sides of the central section.

20 As shown in Fig. 5, it will be noted that the hinges 18 and 19 are offset to project on either side. This construction provides shoulders 20 and when the garment holder is in an open position, the shoulders butt each other forming a stop and causing the garment holder to seek a straight line and form tight joints between the hinged ends of the sections.

The hook 21 is anchored into a cap 22 which is hinged at 23 and when not in use is folded to the dotted position.

Having thus described the invention, what is claimed is:

A garment hanger comprising a body having end sections and an intermediate section pivoted at its ends to inner ends of the end sections and mounting the end sections for swinging movement from an extended position to a folded position flat against the intermediate section, said end sections having upper edges extending at a downward incline from their inner ends to their outer ends to provide tapered end sections, the intermediate section having its upper portion projecting upwardly above the end sections, a cap pivoted to the top of the intermediate section on an axis perpendicular to the pivotal connection between the end sections and the intermediate section for swinging movement from a raised position to a folded position and when folded having its free end terminating above the folded end sections, and a hook carried by said cap for suspending the hanger from an overhead support.
